(57) **CLAIM**

The ornamental design for a beverage dispenser, as shown and described.

DESCRIPTION

FIG. 1 is a front, top, left perspective view of a beverage dispenser according to a first embodiment showing my new design;

FIG. 2 is a front, top, right perspective view thereof;

FIG. 3 is a rear, top, left perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a front, top, left perspective view of a beverage dispenser according to a second embodiment;

FIG. 11 is a front, top, right perspective view of FIG. 10;

FIG. 12 is a rear, top, left perspective view of FIG. 10;

FIG. 13 is a front elevational view of FIG. 10;

FIG. 14 is a rear elevational view of FIG. 10;

FIG. 15 is a left side elevational view of FIG. 10;

FIG. 16 is a right side elevational view of FIG. 10;

FIG. 17 is a top plan view of FIG. 10;

FIG. 18 is a bottom plan view of FIG. 10;

FIG. 19 is a front, top, left perspective view of a beverage dispenser according to a third embodiment;

FIG. 20 is a front, top, right perspective view of FIG. 19;

FIG. 21 is a rear, top, left perspective view of FIG. 19;

FIG. 22 is a front elevational view of FIG. 19;

FIG. 23 is a rear elevational view of FIG. 19;

FIG. 24 is a left side elevational view of FIG. 19;

FIG. 25 is a right side elevational view of FIG. 19;

FIG. 26 is a top plan view of FIG. 19; and,

FIG. 27 is a bottom plan view of FIG. 19.

The broken lines in the drawings depict portions of the beverage dispenser that form no part of the claimed design.
